UNITED STATES PATENT OFFICE.

ABRAM C. MONFORT, OF EAST PROVIDENCE, RHODE ISLAND.

APPARATUS FOR AUTOMATICALLY FEEDING DISINFECTANTS INTO WATER-CLOSET CISTERNS, &c.

SPECIFICATION forming part of Letters Patent No. 634,649, dated October 10, 1899.

Application filed May 2, 1899. Serial No. 715,269. (No model.)

To all whom it may concern:

Be it known that I, ABRAM C. MONFORT, a citizen of the United States of America, and a resident of East Providence, in the county 5 of Providence and State of Rhode Island, have invented certain new and useful Improvements in Apparatus for Automatically Feeding Disinfectants into Water-Closet Cisterns, &c., of which the following is a specification.

10 This invention relates to certain novel improvements in disinfecting apparatus; and it consists, essentially, of a casing containing a reservoir forming a holder for any suitable prepared disinfectant, combined with dispensing or distributing mechanism adapted to be connected with the valve-lever or other operative part of a water-closet tank or cistern employed for washing or flushing the 15 hoppers and urinals of water-closets and similar sanitary furniture, all as more fully hereinafter set forth and claimed.

The object I have in view is to provide a simple and inexpensive means whereby a predetermined quantity of disinfectant may be 20 measured out and automatically fed into the flushing-water contained in the tank whenever the valve-operating or water-controlling mechanism of the tank is brought into use.

By means of the device forming the subject 25 of this invention each charge of flushing-water is automatically "medicated," as it may be termed, by the addition of suitable disinfecting material, which is readily dissolved in the water, thereby forming a solution which 30 serves not only to wash out the hopper or bowl, but at the same time introduces into the system of piping leading to the sewer or discharge-outlet a medium forming a disinfectant and deodorizer, thus neutralizing 35 any poisonous or noxious gases that may have been formed and rendering the surrounding air pure and agreeable.

In the accompanying sheet of drawings, Figure 1 is a front side view of my improved 45 disinfecting apparatus, the several parts being in the normal position, the casing or housing being sectionally represented. Fig. 2 is a similar view showing the relation of the parts while the pull-lever is being operated. 50 The apparatus is shown as mounted above the usual water-closet tank or cistern and also connected with the pendent flexible "pull

chain." Fig. 3 is a transverse sectional view taken on line $x x$ of Fig. 2. Fig. 4 is a longitudinal section taken through the center of 55 the charge-regulating device, and Fig. 5 is an end view of it.

A, again referring to the drawings, designates my improved portable disinfecting apparatus complete. I prefer to make the casing a of wood, the interior of same being readily accessible upon removing the cover c . The casing may be made box-like or rectangular, its height being, say, seven to eight inches when used in connection with the usual 60 water-closet cisterns of dwelling-houses. Mounted within the casing is a reservoir d , having inclined sides terminating at the bottom in a curved form and having a central opening b^2 therethrough. The hopper-like 70 chamber d' of the reservoir is adapted to contain the pulverulent disinfecting material used in the apparatus.

A movable shaft b is mounted below and in practically continuous engagement with the 75 reservoir d . It is provided with a peripheral pocket or measuring-recess b' , registering with the said opening b^2 whenever the shaft is rotated, as shown in Figs. 2 and 3. On the end of shaft b is secured a gear g , meshing 80 into a similar gear g' , secured in turn to a stirrer-shaft h , passing through the lower portion of the reservoir. The last-named shaft is provided with a series of projecting wires or fingers f , adapted to stir or agitate the 85 powder in the reservoir. The said shafts are adapted to be simultaneously rotated through the medium of a small chain or flexible connection m , passing around and fixed to the lower shaft, thence upwardly and around a 90 small wheel p' , thereby carrying it through the casing. The free end of said chain when the apparatus is in service is attached to the usual pull-chain p , as clearly shown. A spring 95 is employed to rotate the shaft back to its normal position whenever the pulling force upon the chain p is relaxed. As drawn, one end of the spring is attached to a pin fixed to the shaft, the other end being secured to the casing. In order to limit the lower shaft's 100 movement, a pin e' , fixed to the shaft, is arranged to strike a similar pin or stop e , extending from the inner surface of the casing.

I may state that as drawn the shaft b is

provided with a single measuring-pocket b' . As thus arranged, the shaft upon making a semirevolution carries the pocket from the charging position (shown in Figs. 2 and 3) to the discharging position. (Shown in Fig. 1.) The base a^2 of the casing is provided with an opening o , through which the charge contained in the pocket is discharged.

In order to adjust or regulate the quantity 10 of disinfecting material constituting each charge taken from the reservoir, I may employ a thin metal sleeve t , slidably mounted on the shaft b , its inner end being provided with a tongue t' , bent down into and filling the pocket b' transversely. As thus constructed the capacity of the pocket may be readily changed, as desired, the sleeve itself being maintained in position on the shaft or spindle by friction.

20 The manner of operation of my improved disinfecting apparatus A is substantially as follows: The device is secured in position on top of the water-closet cistern or tank. B indicates a portion of such a tank. The operating connection m is then attached to the usual pull-chain p , the latter being fastened to the valve-operating lever l or other-well-known mechanism of the tank adapted to control the inflow or outflow of the flushing-water w . Now, first assuming the apparatus to be in the normal position shown in Fig. 1, the user upon pulling the chain p to discharge the impregnated water from the tank into the usual hopper or urinal connected therewith depresses the corresponding end of valve-lever l , thereby at the same time, through the medium of the chain m , rotating the shafts b h , uncovering the opening b^2 of the reservoir, and bringing the measuring-pocket b' in position directly below said opening, the material instantly falling into and filling the pocket, all as shown in Fig. 2. Upon releasing the pull-chain p the force of the spring s quickly rotates the shafts until arrested by the stops e e' , the several parts then being in the normal position shown in Fig. 1, the pocket b' being at the bottom. The spring further serves to produce a jar or shock when the stops are thus suddenly brought together, thereby insuring that the charge of disinfectant is dislodged from the pocket, said charge falling through the opening o into the water w of the tank B and completing the operation. The chemicals thus automatically fed into the 55 water will become dissolved or incorporated therewith preparatory to being discharged from the tank at the next succeeding flushing. It will be seen that the smooth surface of the shaft b in its rotation keeps the reservoir-opening b^2 completely closed at all times, except when the pocket is being filled. The walls of the reservoir d may be made of slightly flexible material, as suitably-prepared paper or fabric, and removably secured to the 60 interior of the casing.

In my improved apparatus for introducing

disinfectants into the flushing-water it will be seen that as drawn the arrangement is such that the measuring-pocket b' registers with the reservoir-opening b^2 whenever the connection p , through which the usual water-controlling valve is operated, is depressed, (see arrow direction, Fig. 2,) thereby at the same time through the medium of the chain m , attached to the connection p , rotating the shaft b until the parts register, as just stated. While the valve is thus being held open the water flows from the cistern into the hopper, &c. When the pull or tension is released, the valve automatically closes, the said connections then returning to the normal position, the spring s at the same time quickly rotating the shaft b , thereby simultaneously closing the reservoir-opening and uncovering the pocket b' . The jar incident to the engagement of the stops e e' insures the discharge of the disinfectant from the pocket into the cistern, where it is dissolved or united with the water preparatory to being discharged from the cistern into the hopper when the next flushing operation takes place.

I claim as my invention—

1. As an article of manufacture, a machine or apparatus for automatically dispensing predetermined quantities of disinfectants into the flushing-water of water-closet cisterns, &c., the same consisting of a stationary reservoir for said disinfectant having an outlet or discharge passage, a rotary spring-pressed shaft or member having a measuring pocket or recess therein adapted to register with said discharge-outlet of the reservoir, and a flexible connection uniting said shaft and the usual water-controlling valve or mechanism of the flushing system, arranged whereby the charge of disinfectant is automatically discharged from the measuring-pocket into the cistern after the water-controlling valve is closed, thereby allowing the thus-discharged disinfectant to dissolve or unite with the water in the cistern before the closet is again brought into use.

2. In a disinfecting apparatus of the kind described, the combination with the apertured reservoir for the disinfectants and a stirrer located therein, of the rotary shaft member provided with a pocket adapted to communicate with the opening in the reservoir, gearing uniting said stirrer and shaft members, a spring for rotating the shaft whereby the charge of disinfectant is adapted to be transferred from the reservoir into the flushing-water of the water-closet cistern or tank, stops for limiting the rotary movement of the shaft, and a flexible connection secured to the shaft and adapted to be attached to any suitable part of the water-controlling mechanism of the flushing system, substantially as described.

3. In a disinfecting apparatus for water-closet cisterns, &c., the combination with a suitably-arranged reservoir containing the disinfecting material, of a rotary shaft mem-

ber provided with a measuring pocket or recess arranged to register with an opening formed in said reservoir, a sleeve or other analogous member slidably mounted on said shaft provided with a tongue, filling said pocket transversely, whereby the capacity of the pocket may be adjusted and a connection attached to the shaft and also adapted to be attached to the water-controlling mechanism

of the flushing system, substantially as described.

Signed by me at Providence, Rhode Island, this 1st day of May, A. D. 1899.
